Primary Examiner — Cynthia Ramirez

(57) **CLAIM**

The ornamental design for a car trash can, as shown and described.

DESCRIPTION

FIG. 1 is a first perspective view of a car trash can showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an opening state of the car trash can thereof;

FIG. 10 is another opening state of the car trash can thereof;

FIG. 11 is an enlarged view of the selected portion 11 in FIG. 1; and,

FIG. 12 is an enlarged view of the selected portion 12 in FIG. 2.

The broken lines shown in the drawings depict portions of the car trash can that form no part of the claimed design. The dash-dot broken lines demarcate enlarged areas and form no part of the claimed design.

1 Claim, 12 Drawing Sheets
